UNITED STATES PATENT OFFICE.

AMOS E. WHIPPLE, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS.

TOOL FOR REMOVING TRAVELERS FROM SPINNING AND TWISTING RINGS.

Application filed February 4, 1927. Serial No. 165,831.

This invention relates to an improved instrument for facilitating the removal of travelers from spinning and twisting rings.

In the customary method of removing 5 travelers from rings by a sharp blow from a hammer it frequently happens that the rings are so damaged that it is necessary to replace them with new ones thus causing considerable expense for new rings and in the labor 10 of replacing them.

The object sought to be attained in my present invention is to produce a comparatively inexpensive instrument, by the use of which a traveler may be easily and quickly 15 removed from its ring without causing any damage to the latter.

Another object of my invention is to provide means whereby injury to the operative from any flying particles of a broken traveler is prevented. 20

To these ends my invention consists essentially of a pair of levers joined together intermediate of their ends by a ring joint swingable about a fulcrum spacing each lever into forward and rear arms. The forward arms provide jaws for insertion between the points of the traveler, and the rear arms of the levers serve as handles for the application of force by the hand of the operator whereby the jaws inserted into the traveler either break it in two or spread it open sufficiently to free it from the flange of 25 the ring. A screen fixedly connected to the top of one jaw and projecting over the traveler being removed prevents flying particles of the broken traveler from hitting the face of the operative.

The various novel features of my invention will be fully described in the subjoined 40 specification and particularly pointed out in the claim.

In the accompanying drawings:—Figure 1 is a fragmentary portion, perspective view of a spinning machine ring rail with a ring 45 and its traveler mounted thereon showing the manner of removing the traveler from the ring by means of my improved tool. Figure 2 is a plan of the traveler removing tool. Figure 3 is a side elevation of the 50 same. Figure 4 is an enlarged sectional elevation on line 4—4 of Figure 2 showing the

construction of the joint of the instrument. Figure 5 is a fragmentary portion, plan view of one of the levers, showing its construction at the joint, and Figure 6 is a plan 55 of a joint locking ring.

In the drawings, wherein for the purpose of illustration is shown a preferred form of my invention comprising a pair of levers 10 and 11 joined together at their common fulcrum 12 by a joint consisting of semi-circular grooves 13 and semi-circular raised portions 14 formed in both sides of each lever. Rings 15 loosely mounted in each groove 60 lock the levers together about the fulcrum 12, a semi-circular bearing 16 on each lever coacting with the surface of said fulcrum. 65 At each end of the fulcrum a washer 17 is fixed thereby maintaining the fulcrum and locking rings in proper relation with the levers. 70

Each lever consists of a forward arm or jaw member and a rear arm or handle member. The forward arm is tapered to a blunt point 18 for ready insertion inside of a traveler, the rear arm serving as a grip for the hand of the operator. A flat steel spring 19 coacts between the rear arms of the levers to maintain the jaw members together prior to their insertion into the traveler. To prevent 75 possible injury to the operator by particles of steel flying from a traveler while it is being acted on by the removing tool, a perforated screen 20 is attached to the tool just over the jaws so that it imposes a guard between the jaws and the face of the operator. Preferably the screen is held in a frame 21 fastened by a rivet 22 to one of the jaw members. 80

It is to be understood that the form of my 85 invention herewith shown and described is to be taken as a preferred form of the same, and that various changes in shape, size and arrangement of parts may be resorted to without departing from the spirit of the invention or the scope of the subjoined claim. 95

I claim:—

A tool for removing travelers from spinning and twisting rings comprising a pair 100 of levers each having a forward and a rear arm, a joint connecting the levers located intermediate of the ends of the arms, a ful-

crum for said levers on which the joint is swingable, coacting tapered jaws formed in the forward pair of arms, handles formed on the rear pair of arms for the manual actuation of said jaws, resilient means coacting between said handles to maintain said jaws in a closed relation with each other, a frame

extending over the top of the jaws and rigidly fixed to one of them, and a perforated screen supported by said frame.

In testimony whereof, I have signed this specification.

AMOS E. WHIPPLE.
